(57) **CLAIM**

The ornamental design for the seismic sway brace fitting, as shown and described.

DESCRIPTION

FIG. 1 is a perspective view of a seismic sway brace fitting according to our new design, wherein a fastener, a pin, and a yoke are shown in broken lines shown in an alternate environment;

FIG. 2 is a front elevational view thereof;

FIG. 3 is a right elevational view thereof;

FIG. 4 is a top plan view thereof;

FIG. 5 is a rear elevational view thereof;

FIG. 6 is a left elevational view thereof; and,

FIG. 7 is a bottom plan view thereof.

The broken lines in the drawings illustrate portions of the seismic sway brace fitting, which form no part of the claimed design.
